PLEATING DEVICE

Walter J. Houser, San Marcos, Calif.

Application September 12, 1944, Serial No. 553,687

7 Claims. (Cl. 38—108)

1

This invention relates to a device for facilitating the arrangement of pleats in fabrics, and the holding of fabrics in a pleated condition while they are being ironed or pressed.

An object of the invention is to provide a simple, durable, and economical construction that can be readily applied to a conventional ironing board, and which will enable the fabric to be pleated to be positioned and arranged thereunder to secure the desired pleats and thereafter firmly pressed and clamped in position on the ironing board so that the fabric will not be disturbed during the ironing or pressing operation.

Another object of the invention is to provide a pleating device which is so arranged that it may accommodate itself to uneven or slightly concaved ironing boards.

A further object of the invention is to provide a pleating device wherein there is an engaging bar adapted to engage the fabric to be pleated and which has associated therewith a flexible toothed clamping member for clamping the fabric firmly against the ironing board after the pleats have been arranged, the clamping member and engaging bar being so connected together that relative movement therebetween may take place during the clamping operation.

With the foregoing and other objects in view, which will be made manifest in the following detailed description and specifically pointed out in the appended claims, reference is had to the accompanying drawings for an illustrative embodiment of the invention, wherein:

Figure 1 is a partial view in perspective of an ironing board illustrating the pleating device, embodying the present invention as having been applied thereto and illustrating it in applied position over a section of fabric in which the pleats have been arranged;

Fig. 2 is a partial view in vertical section through the clamping apparatus utilized for mounting the device on an ironing board;

Fig. 3 is a sectional view taken substantially upon the line 3—3 upon Fig. 1 in the direction indicated, illustrating in full lines the pleating device in clamping position, and in dotted lines the manner in which the pleating device may be elevated therefrom;

Fig. 4 is a partial view in vertical section illustrating the positions assumed by the parts prior to clamping the fabric in its pleated condition;

Fig. 5 is a vertical section taken substantially upon the line 5—5 upon Fig. 3; and

Fig. 6 is a partial view in section illustrating the detail of construction.

Referring to the accompanying drawings wherein similar reference characters designate

2

similar parts throughout, the improved pleating device comprises a suitable base made up of two members 10 and 11 that are telescopically arranged. The member 11 is preferably hooked as at 12 so as to be receivable over one edge of an ironing board 1. The other member 10 may be similarly hooked and equipped with a suitable thumb screw 13 for clamping it to the ironing board. On the member 10 of the base there is secured a suitable journal 14 within which is rotatable a rockshaft 15 having at its outer ends parallel arms 16 and 17. These arms are spaced from each other a distance approximately equal to the width of the ironing board. The forward ends of the arms extend inwardly toward each other and are secured to leaf springs 18 and 19, the ends of which are slidably receivable in recesses in the top of a clamping bar 20. The clamping bar is preferably formed of plastic or similar material that possesses some degree of flexibility. A limited degree of flexibility in the clamping bar is desirable inasmuch as ironing boards frequently have some transverse warpage or are slightly concave on their upper surface. If the clamping bar 20 is slightly flexible it may conform to the shape of the upper surface of the ironing board when pressure is applied thereto.

The clamping bar 20 has a series of teeth 21 preferably formed integral therewith and extending downwardly from its underside. This row of teeth is arranged longitudinally of the clamping bar at approximately its center so as to extend transversely across the ironing board. Beneath the clamping bar 20 there is disposed an engaging bar 22 which has a longitudinally extending slot 23 formed therein adapted to have the teeth 21 extended therethrough. This engaging bar 22 may be formed of wood or any other suitable material. 24 is a section of sponge rubber or like material that is readily compressible. This material is arranged in strips between the clamping bar and the engaging bar on opposite sides of the teeth 21 and is cemented or otherwise secured to these bars. In this manner, the two bars 20 and 22 are permanently associated together but relative movement therebetween is permissible by compressing the strips 24, compare Figs. 3 and 4. Adjacent the center of the journal or knuckle 14 there is a slot 27 on one side of which ratchet teeth 27a are arranged. A manually operable lever 28 is rigid with the rockshaft 15 and extends through this slot. This lever presents an edge 29 engageable with any of the ratchet teeth to lock the rockshaft in a position wherein it holds the clamping bars in engagement with the work, as illustrated in Fig. 3.

The length of the slot 27 is such that the rock-shaft may be swung through an arc of little less than 180° so that the clamping bar and the engaging bar may be lifted from the full line position shown in Fig. 3 through the dotted line position illustrated in this figure, and be positioned on the opposite side of the journal 14 from the position illustrated to completely expose the work on the ironing board.

The operation and advantages of the improved pleating device are as follows: The fabric F that is to be pleated may be positioned on the ironing board and the pleats partially set. The clamping and engaging bar may then be swung over the work and allowed to rest thereon by gravity thus forming a type of weight that will facilitate the setting of the pleats. Inasmuch as the arms 16 and 17 are spaced from each other approximately the width of the ironing board the fabric F may be grasped on both sides of the engaging bar 22 in setting the pleats. When all of the pleats have been set the handle or lever 28 is swung forwardly and downwardly with considerable effort to cause the compressible strip 24 to be squeezed and compressed and assume a position as illustrated in Fig. 3, wherein the teeth 21 are projected slightly through the slot 23 in the engaging bar and are caused to firmly engage and hold the pleated fabric in engagement with the ironing board. The pleats may then be ironed in the fabric forwardly of the engaging bar and when this is completed the apparatus may be swung clear of the fabric and that portion of the fabric beneath the engaging bar and between the engaging bar and the base may have the pleats ironed therein. During the time that the compressible strips 24 are compressed, it will be understood that the lever 28 may be locked in position by causing its edge 29 to engage one of the teeth 27a. Disengagement is permitted by merely moving the lever 28 a short distance longitudinally to permit of disengagement.

From the above-described construction it will be appreciated that an improved pleating device is provided which is of relatively simple, durable, and economical construction, and which may be readily applied to any conventional ironing board. The pleating device will conform or adapt itself to the shape or condition of the top surface of the ironing board and will facilitate the adjustment or formation of the pleats prior to the fabric being clamped up. Thereafter, the fabric may be firmly held in its pleated condition while the pleats are being pressed therein without danger of the ironing operation working the fabric loose from beneath the clamping bar.

Various changes may be made in the details of construction without departing from the spirit and scope of the invention as defined by the appended claims.

I claim:

1. A pleating device comprising a base, means for clamping the base upon an ironing board, an engaging bar engageable with the work placed on the ironing board and a toothed clamping bar movable relatively to the engaging bar toward and away from the work, and means on the base for yieldably forcing the clamping bar toward the ironing board whereby its teeth may be advanced relatively to the engaging bar.

2. A pleating device comprising a base, means for clamping the base upon an ironing board, an engaging bar engageable with the work placed on the ironing board and a toothed clamping bar movable relatively to the engaging bar toward

and away from the work, and means on the base for yieldably forcing the clamping bar toward the ironing board whereby its teeth may be advanced relatively to the engaging bar, said clamping bar being bendable.

3. A pleating device comprising an engaging bar engageable with the work and having a slot therethrough, a clamping bar having teeth adapted to be projected toward the work through

10 the slot, compressible means between the engaging bar and the clamping bar normally holding the clamping bar in a position wherein its teeth are retracted, and means for urging the clamping bar toward work placed on an ironing board.

15 4. A pleating device comprising an engaging bar engageable with the work and having a slot therethrough, a clamping bar having teeth adapted to be projected toward the work through the slot, compressible means between the engaging bar and the clamping bar normally holding the clamping bar in a position wherein its teeth are retracted, and means for mounting said bars

20 upon an ironing board and yieldably forcing the clamping bar toward work placed on the ironing board.

25 5. A pleating device comprising an engaging bar engageable with the work and having a slot therethrough, a clamping bar having teeth adapted to be projected toward the work through

30 the slot, compressible means between the engaging bar and the clamping bar normally holding the clamping bar in a position wherein its teeth are retracted, and means for mounting said bars

35 upon an ironing board and yieldably forcing the clamping bar toward work placed on the ironing board and locking the clamping bar in clamping position.

6. A pleating device comprising a bar, means for clamping the bar upon an ironing board, a knuckle on the base, a rockshaft rotatable in the

40 knuckle, yieldable arms on the rockshaft, a clamping bar pivotally mounted upon the yieldable arms, teeth on the underside of the clamping bar, an engaging bar having a slot therethrough through which the teeth are extendable toward the work placed on the ironing board, and compressible means between the clamping bar and engaging bar.

45 7. A pleating device comprising a bar, means for clamping the bar upon an ironing board, a knuckle on the base, a rockshaft rotatable in the knuckle, yieldable arms on the rockshaft, a clamping bar pivotally mounted upon the yieldable arms, teeth on the underside of the clamping bar engageable with work placed on the ironing board, an engaging bar having a slot therethrough through which the teeth are extendable, compressible means between the clamping bar and engaging bar, and means for releasably locking the rockshaft in adjustable position.
